UNITED STATES PATENT OFFICE.

ANDREW PAUL WATT, OF MANCHESTER, NEW HAMPSHIRE.

KNITTING-MACHINE NEEDLE.

1,127,132.

Specification of Letters Patent.

Patented Feb. 2, 1915.

Application filed August 6, 1913. Serial No. 783,296.

To all whom it may concern:

Be it known that I, ANDREW PAUL WATT, a citizen of the United States, residing at Manchester, county of Hillsboro, State of

5 New Hampshire, have invented an Improvement in Knitting-Machine Needles, of which the following description, in connection with the accompanying drawing, is a specification, like characters on the drawing

10 representing like parts.

This invention relates to knitting machine needles and to the method of making the same, and has for an object to provide a needle which will be reliable and 15 not subject to breakage at the butt, and at the same time which will provide a proper bearing at the heel to keep the needle from tipping in its slot and to provide a method of manufacture of such needles.

20 Knitting machine needles as most commonly manufactured are made from wire bent to form the butt and heel, and then flattened. The butt of the needle as so formed consists of a loop of wire, which 25 at the outer end is bent double upon itself and therefore seriously weakened, the distortion of the metal and the internal stresses resulting in frequent breakage. Some types of machines are so arranged 30 that the broken ends of the needles fall among the working parts and cause serious trouble, for which reason it is particularly important to provide a type of needle in which the breakage will be reduced to a 35 minimum.

By the present invention I have devised a construction of needle and a method of manufacturing needles from wire, in which the butt is formed by the bent up end of 40 the wire body. I form the heel integral with the butt by shaping a part of the metal to form the butt and a part to form the heel. This may be done by drawing out the metal at the angle of the butt after the 45 end of the body has been bent to form the heel, or by dividing this end of the body either before or after bending and forming the heel from one divided end. If the end is divided first only one part is bent and 50 the other part is left straight to form the heel. The shank, terminating in a yarn receiving hook is formed as usual by drawing out, bending, etc., and may be formed either as a latch needle or as a spring hook 55 needle.

The novel features of the invention will be fully described in the following specification and particularly pointed out in the claims.

Referring to the drawing, Figure 1 is a 60 side view of a knitting machine needle of the type known as a latch needle, the end having been bent up to form a butt, and the shank and butt having been flattened. Fig. 2 is a side view of a portion of the 65 needle showing the butt after the metal has been drawn out at the apex of the angle to form the heel. Fig. 3 is a view similar to Fig. 2, showing the heel as formed by drawing out the metal at the angle in a somewhat 70 different manner. Fig. 4 is a side view illustrating a different method of manufacture showing the butt as partially formed. Fig. 5 is a view showing the butt after the surplus stock has been removed. Fig. 6 is a 75 similar view of the same parts after the metal has been drawn out to form the heel. Fig. 7 is a view similar to Figs. 2 and 3 showing the heel drawn out to a different shape. Fig. 8 is a side view showing the 80 blank after the first step of another method of manufacture in which the end of the needle body is split and one part bent to form the heel. Fig. 9 is a similar view showing the blank after the surplus metal 85 has been cut away from the shank and the divided portion bent down to form the heel, and Fig. 10 is a similar view showing the bent back portion as drawn out to form a more extended heel. 90

Referring to the drawing in detail 1 indicates the body of a needle having a shank 2 terminating in a yarn receiving hook 3 and having the other end bent at an angle to the shank to form a butt 4. In order 95 that the needle may not tip in the knitting machine when it is drawn backwardly by the cam acting upon the butt, it is necessary that it should have a heel portion projecting beyond the butt on the edge opposite 100 from the shank and this heel portion must present a bearing in alignment with the back edge of the shank. In Fig. 2 I have shown this heel portion as formed at 105 5 by drawing out the metal at the apex of the angle formed by the shank and butt. This heel is thinner than the rest of the needle, but I find this is not a serious disadvantage as there is sufficient stock to provide the necessary strength, there being 110

comparatively little strain upon this heel portion, and such strain as there is is in the direction of its greatest strength.

In Fig. 3 I have shown a heel portion at 5 6, formed in substantially the same manner as the heel portion shown in Fig. 2, but of a somewhat different shape, and less metal has been drawn out from the angle to form such heel portion. It will be noticed that in 10 this form the heel portion 6 does not bear for its full length against the knitting cylinder, but there is no particular disadvantage in such a bearing, it being sufficient that the heel shall bear at a point somewhat 15 distant from the butt to keep the needle from tipping.

In Figs. 4, 5, and 6 I have illustrated another method of construction. As shown I use a considerably larger stock bending the 20 wire at a right angle to form the butt. I then flatten the needle until it is of the desired thickness, then reduce the shank in the usual manner down to the butt and cut away the surplus stock at the rear of the butt, as 25 shown at 7. When this surplus portion is removed the butt of the needle will be of the necessary shape and size, and there will be a projecting portion 8 which may be drawn out to form an extended heel, as shown, for 30 example, at 9.

In Figs. 8, 9, and 10 I have shown another method of providing the needle with an extended heel portion. In accordance with this method I make the needle from wire 35 which is sufficiently large, so that when bent and flattened and the shank reduced, it will be of the form shown in Fig. 8, and of sufficient width to provide a butt 10 and a heel 11. This bent portion is then slit as shown 40 at 12, leaving the butt 10 of a required size. The slit off portion is then bent and worked back as shown in Fig. 9, to form a heel presenting a bearing 14 in alignment with the edge 15 of the shank of the needle. If desired, this heel may be drawn out as shown 45 at 16 in Fig. 10 to form a more extended bearing.

Thus this invention in all forms provides a knitting machine needle having a suitable 50 butt and a heel presenting a bearing beyond the butt and in line with the back of the needle. In a needle made in accordance with this invention, the metal of the butt and heel is homogeneous thus eliminating 55 the objections of unreliability and expense due to welding or similar operations; the grain of the metal extends longitudinally of the butt, thus eliminating the sharp bend of the grain of the metal at the end of the 60 butt which has always been a great source

of weakness; and all the advantages due to the use of wire which has always been found superior to sheet metal from which needles are sometimes made by stamping or punching operations are retained. 65

The invention in its broader aspect is not concerned with the particular method of drawing out the metal to form the heel as this can be done by various well known processes of drawing, hammering, spinning 70 and rolling.

Having described my invention what I claim as new and desire to secure by Letters Patent is:

1. A wire knitting machine needle comprising a shank, a yarn receiving hook at one end of said shank, a butt near the opposite end of said shank projecting at an angle and being of homogeneous metal, the grain of which butt all extends longitudinally thereof, and an integral heel portion extending from the free edge of said butt and presenting a bearing in line with the back of the shank. 75

2. A wire knitting machine needle comprising a body having a shank terminating in a yarn receiving hook and having the other end bent at an angle to the shank to form a butt, the metal of the body being drawn out to form a heel projecting from 80 the edge of the butt opposite the shank, and presenting a bearing in line with the back of the shank, whereby the needle presents a solid butt with a bearing beyond 90 each edge of the butt at the back of the 95 needle.

3. A wire knitting machine needle comprising a body portion having a shank terminating in a yarn receiving hook, said body portion being divided at the opposite 100 end and the separate portions forming respectively a butt and a heel, said heel presenting a bearing in alignment with the back of the shank at the opposite edge of the butt from said shank. 105

4. A wire knitting machine needle comprising a body having a shank terminating in a yarn receiving hook and having the other end bent at an angle to the shank to form a butt, part of the metal of such end 110 being bent back to form a heel portion presenting a bearing in line with the back of the shank.

In testimony whereof, I have signed my name to this specification, in the presence of 111 two subscribing witnesses.

ANDREW PAUL WATT.
